H. C. JOHANSEN

COMPRESSOR UNLOADING MEANS

Filed Oct. 29, 1921

UNITED STATES PATENT OFFICE.

HARRY C. JOHANSEN, OF CHICAGO, ILLINOIS, ASSIGNOR TO SULLIVAN MACHINERY CORPORATION, A CORPORATION OF MASSACHUSETTS.

COMPRESSOR-UNLOADING MEANS.

Application filed October 29, 1921. Serial No. 511,380.

To all whom it may concern:

Be it known that I, HARRY C. JOHANSEN, a citizen of the United States, residing at Chicago, in the county of Cook and State of Illinois, have invented certain new and useful Improvements in Compressor-Unloading Means, of which the following is a full, clear, and exact specification:

My invention relates to compressor unloading means.

An object of my invention is to provide an improved compressor unloading means, and more especially an improved compressor unloading means of the auxiliary type adapted to be used with a compressor having an intake type unloader, and to avoid the compression of air which might leak past the intake unloader valve when the compressor is turning over unloaded, from a partial vacuum to receiver pressure and so the generation of excessive temperatures. Other objects and advantages of my invention will be apparent in the course of the following specification and appended claims.

In the accompanying drawings, I have shown for purposes of illustration one embodiment which my invention may assume in practice.

In these drawings,—

Fig. 1 is a side elevation of a compressor provided with my improved unloading means.

Fig. 2 is a detail view, partially in section, of the high pressure cylinder, showing the relation of the unloading means thereto.

Fig. 3 is a central longitudinal section through my improved unloading mechanism.

Fig. 4 is a transverse section on the line 4—4 of Fig. 3.

This mechanism is an improvement upon the mechanism illustrated in my copending application for compressors, Serial No. 295,482, filed May 7, 1919.

Referring to the drawings in which I have shown the illustrative embodiment of my invention, and particularly to Fig. 1, it will be noted that I have shown a compressor of the angle compound type having a horizontal low-pressure double acting cylinder 1, a high pressure double acting vertical cylinder 2, and driving mechanisms for the pistons reciprocable in these cylinders whereby the two stages are operated

from the single crank shaft 3. The intake to the low pressure cylinder 1 is through an inlet pipe 4 and is controlled by an automatically operated unloading means 5, such as is in common use on compressors, to unload the compressor by closing the intake thereto when the pressure in the receiver or pressure discharge line exceeds a predetermined desired amount. The partially compressed air or other fluid passes from the low pressure cylinder through intercooler 6 to the high pressure cylinder 2 and thence by way of a discharge pipe 7 to the point of use or to a receiver. When the pressure in the receiver, or other point to which the pipe 7 is connected, rises above the predetermined desired pressure named, the unloading means 5 is operated by automatic means which are so well known as not to need description at this point, and the intake to the compressor is thereby closed and hence the compressor, if there is no leakage, no longer operates to compress air drawn in through the line 4 and to discharge it to the line 7.

In practice, it is possible that the intake controlling mechanism may not completely close off the connection between the pipe 4 and the low pressure cylinder 1 or that there may be other leakage, perhaps through the stuffing boxes, and under those circumstances the continued reciprocations of the piston in the low pressure cylinder may draw in a reduced charge of air into the low pressure cylinder which is insufficient to fill it at atmospheric pressure. Therefore, at the end of the suction strokes the cylinder may have in it air at a relatively low pressure, which air will be compressed and forced into the intercooler. This air which leaks by the intake unloading mechanism and is passed into the intercooler is not materially compressed in the low pressure cylinder by reason of the fact that the intercooler pressure is pumped down to a partial vacuum by the high pressure cylinder. Therefore, in the high pressure cylinder, since the same condition prevails as in the low pressure cylinder, i. e. that at the end of the suction stroke of the high pressure piston there is a partial vacuum in the high pressure cylinder, there occurs upon the compression strokes of the piston a compression of a charge of air from perhaps three pounds or more absolute up to 110

the pressure in the discharge line 7, say 100 pounds gage or more. As a result of the number of compressions during this operation, a very considerable amount of heat is generated which at times may be sufficient to explode mixtures of gas and air formed in the high pressure cylinder from vaporization of the lubricating oil, or, if this does not occur, to carbonize the lubricant in the high pressure cylinder and so reduce the lubricating efficiency. To avoid difficulty of this kind and similar trouble, I have mounted upon the high pressure cylinder 2 my improved unloading mechanism which avoids the compression of fluid up to discharge line pressure and instead permits the discharge of fluid from the high pressure cylinder to the atmosphere at pressures not greatly exceeding atmospheric pressure.

My improved unloading mechanism is generally designated 8 and comprises a casing made up of three parts,—two end sections 9 and 10 and a central section 11. The end sections are bored to provide coaxial cylinders 12 and 13 and in their normal position these cylinders lie with their axes horizontal. The central section is provided with a slightly enlarged bore and at its opposite ends has valve seating surfaces 14 and 15. Reciprocable in the cylinders 12 and 13 are pistons 16 and 17 which are closed at their adjacent ends and provided with rims 18 and 19 respectively adapted to seat upon the valve seating surfaces 14 and 15. These pistons, as illustrated, have open rear ends, but this is not requisite and the rear ends thereof may be closed if desired. Between the adjacent closed ends of the pistons 15 and 16 is disposed a spring 20 which is of slightly greater length than the distance between the valve seating surfaces 14 and 15. Each of the cylinders is provided with an enlarged annular counterbore at its end adjacent the central section 11, these counterbores being designated respectively 22 and 23. The rims 18 and 19 are adapted to cooperate with the remote ends of these counterbores to limit the unseating movements of the valve pistons 15 and 16. The rear end of each cylinder is connected to the counterbore of the other, the rear end of cylinder 12 being connected by a passage 24 to the counterbore of the cylinder 13, while the rear end of the cylinder 13 is connected to the counterbore 22 of the cylinder 12 by a passage 25. Pipes 26 and 27 connect the passages 24 and 25 to the opposite ends of the cylinder 2 at points so located that the connections will not be wholly overrun by the piston. The bore of the central section of this unloading means is connected by a port 28 controlled by a spring pressed end seating valve 29 with an atmospheric vent 30.

The mode of operation of this mechanism will be readily apparent. When the compressor is operating loaded, the pressure in the lines 26 and 27 will vary between intercooler pressure and compressor discharge pressure. As a result, the valves 15 and 16 will remain constantly seated. When the intake to the low pressure cylinder is closed, the low pressure cylinder will no longer supply any appreciable amount of air to the intercooler and the intercooler pressure will be rapidly pumped down by the high pressure cylinder. There will then promptly come a time when the pressure on one of the suction strokes of the piston will fall low enough to cause the air in the chamber between the valves to open the valve whose rear end is connected to the end of the cylinder in which suction is taking place before the pressure on the other side of the piston gets high enough to keep the valve closed. This will result in the discharge through port 28 of the pressure in the high pressure cylinder as soon as it reaches a little above atmospheric pressure, and of course at such a low temperature that no injurious result is possible. The mechanism will thereafter act as a relief means, connecting the working (i. e. compressing) sides of the piston to atmosphere whenever the pressure is high enough, until the cylinder is reloaded. It will be evident that as one valve seats the spring, which is just a little longer than the distance between the two valves when seated, will cushion its seating and will aid in the unseating of the valve which is about to open. This arrangement produces a more certain action of the valves and practically eliminates all slapping of the valves upon their seats and breakage resulting from that cause.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. An unloading mechanism for a compressor cylinder comprising a casing, a plurality of valves therein, a connection with the atmosphere, passages leading from each end of the cylinder to said casing and having their communication with the atmospheric connections controlled by said valves, each of said valves being governed as to opening by the pressure conditions in that one of said connections which it does not control, and spring means cooperating with said valves and tending to unseat them when both are seated.

2. An unloading mechanism for a compressor cylinder comprising a multipart casing consisting of spaced cylinder sections connected by a central section, cylinder bores in said cylinder sections, a central bore in said central section in alinement with said cylinder bores and surrounded by seat areas, counterbores in said cylinder sections adjacent said central sections, pins 5 tons disposed in said cylinders and having enlarged heads reciprocable in said counterbores and adapted to cooperate with said seat areas, a spring disposed in said central bore and of a length when uncompressed 10 greater than the distance between said pistons when the latter are seated, and connections each connecting one end of said com- 15 pressor cylinder with one of said counterbores and the opposite end of the opposite cylinder. 20
3. An unloading mechanism for a compressor cylinder comprising a casing, a plurality of oppositely disposed valves therein, a connection with the atmosphere between said valves, connections leading to the opposite ends of the cylinder controlled by said valves, a spring between said valves of a length slightly greater than the distance between said valves when they are in their most proximate positions to each other, 25 and means for causing said valves to alternately act as relief valves. 30

In testimony whereof I affix my signature.
HARRY C. JOHANSEN.
